UNITED STATES PATENT OFFICE.

IRVING C. JENNINGS, OF SOUTH NORWALK, CONNECTICUT, ASSIGNOR TO NASH ENGINEERING COMPANY, OF SOUTH NORWALK, CONNECTICUT, A CORPORATION OF CONNECTICUT.

AIR AND WATER PUMP IN COMBINATION.

Application filed July 9, 1923, Serial No. 650,519. Renewed April 12, 1928.

The present invention relates to pumping apparatus and particularly to that type which is adapted for use in connection with systems where it is desired to handle air and 5 water under pressure less than atmospheric such, for example, as vacuum steam heating systems. The pumping apparatus shown and described herein embodying the invention is particularly designed for use in connection 10 with the flat boxes of paper machines. Heretofore the air and water pumps for such flat boxes have been separate and driven by individual motors. According to the present invention the air and water pumps are both 15 mounted on a single shaft and driven from a single source of power, which may be a motor directly connected to the shaft or a belt drive.

One of the principal features of the present invention resides in the construction of the pumping unit, the air and water pumps being removably secured together in such manner that any one of a series of water pumps can be combined with any one of a 25 series of air pumps. As the construction is much simpler than the prior combined units, it is possible to manufacture a pumping unit at less cost than heretofore. There is also a great saving in the capital tied up in manufactured stock at the factory and agents warehouse. To illustrate, according to the present invention, suppose there are three water 30 pumps and three air pumps. Any one of the water pumps can be combined with any one of the air pumps to make a pumping unit. Consequently with the said three water pumps and three air pumps, nine combinations of pumping units are possible. Thus instead of being obliged to manufacture and carry in 35 stock nine pumping units of the old style (that is to say nine units each consisting of a water pump and an air pump) according to the present invention it is only necessary to carry three water pumps and three air 40 pumps.

Another feature of the invention resides in the construction of the pumps whereby the opposite heads are removable for the purpose of giving access to the interior of the pumps 45 and the impellers.

Another feature of the invention resides in providing the inlets and outlets for both pumps in the main portions of the pump

55 housings, so that the heads may be removed without disconnecting any piping.

Another feature resides in the structure and arrangement of the unit whereby no stuffing box is required between the air and water pump.

Another feature resides in the arrangement 60 whereby hydraulic balance of the impeller of the water pump is obtained, thus reducing and practically eliminating any axial thrust on the shaft of the pumps.

Another feature resides in the provision of 65 an improved means for adjusting the shaft of the pumps axially, so that the impeller of one of the pumps may be accurately and delicately adjusted axially, the impeller of the other pump being held against axial movement by the walls of its casing.

Other objects and features of novelty will be apparent from the description taken in connection with the drawings, in which:

Fig. 1 is a side elevation of the pump mechanism embodying the invention with adjacent attached parts of the system in which it is used;

Fig. 2 is an end view of the mechanism shown in Figure 1 looking from the right;

Fig. 3 is a vertical longitudinal section through the pump mechanism embodying the invention;

Fig. 4 is a horizontal section on the line 4—4 of Figure 3;

Fig. 5 is a vertical section on the line 5—5 of Figure 3 looking to the right;

Fig. 6 is an enlarged longitudinal section of the adjustable ball bearing support for the drive shaft shown in Figure 3 at the 80 right; and

Fig. 7 is a side view of one of the ring nuts used in said adjustable bearing.

Referring first to Figures 1 and 2 which show side and end views of the pump mechanism together with the adjacent parts of the system with which it may be connected in use, there is a vertical container or tank 10 in fixed position adapted to receive air and water through suitable piping which enters it through the header 11 carried by the container 10 slightly above its central portion. This water and air may be that from the flat boxes in paper mills but it is of course adapted for receiving air and water 105 coming from other sources.

A centrifugal water pump in the housing 12 draws water from the lower portion of the container 10 through inlet pipe 13 shown in dotted lines in Figure 1. The water thus drawn in is discharged by the centrifugal water pump through pipe 14 and is conveyed to any point desired for use. The pipe 15 at its lower end is connected to the top of the water pump housing and having its other end connected to the upper part of the container 10 is for the purpose of allowing any air which may enter the water pump through the inlet when the water is too low or by leakage to escape and return to the upper part of the tank. Air in the container 10 is drawn off through pipe 16 connected to its upper end by the air pump in the housing 17 entering at the rear of the housing, as shown in Figure 1, the air being discharged from the air pump through the outlet opening 18 into the open air as shown. If desired however a pipe 95 Fig. 2 may be connected to the outlet 18 so as to convey the air to a distance before it is discharged. In commercial use of the device some known form of automatic control is desirable and should be used so as to maintain a substantially uniform water level in the container 10 and substantially uniform air pressure in that container above the water. Such mechanism however is well known in the art and forms no part of the present invention and is therefore not shown or described in this application. An automatic control mechanism where the pumps are operated by an electric motor in a similar system is disclosed and claimed in my prior Patent No. 1,447,854 granted March 6, 1923. As above stated, the present invention relates to the structural characteristics of the pump mechanism.

Referring now to the pump mechanism it will be noted from an inspection of Figures 1, 3, and 5 that the air pump housing 17 is supported on a stand 19 by longitudinal flanges 20 having outturned lower end portions fitting the surface of the stand 19 and these flanges are formed on the main body portion 21 of the housing. They constitute the support for not only the air pump housing but also for the water pump housing and the drive shaft. The air pump housing includes the main body portion 21 above mentioned which has the end wall 22 spaced a material distance from the adjacent end wall 23 of the casing for the rotor 24, thus forming a space for the air between them. The housing 17 of the air pump also includes the head portion 25 which is made separately from the main body portion, the two portions being divided on substantially a vertical plane at the end of the rotor and the end 26 of the rotor casing constitutes a part of the header portion. This end wall 26 of the rotor casing is spaced from the end wall 27 of the header a material distance so as to form an air space between

them. A drive shaft 28 passes centrally through the two portions of the air pump housing and is keyed to the inner cylindrical or hub portion 29 of the rotor so as to rotate together but the connection is such as to permit relative longitudinal movement between the shaft and the rotor.

The inlet pipe connection 30, as shown in Figures 4 and 5, is a part of the main body portion 21 and it has next to the periphery of the rotor casing an enlarged portion 31 extending partly around the rotor casing and having a slot 32 (see Figure 4) on the side next to the head portion 25 adapted to permit air to enter and pass into the head portion and also being connected to the space between the end wall 22 of the main body portion and the end wall 23 of the rotor casing. The head portion 25 has an enlarged sleeve 33 connecting the end wall 26 of the rotor casing and the end wall 27 of the header and it rotatively fits shaft 28 having a stuffing box 34 at its outer end to carry packing making an air-tight contact. The head portion 25 has an outwardly extending portion 35 adjacent the enlarged portion of the inlet connection 30 and fitting it at 36 on the outer side of its opening 32 whereby the air may enter the header through an opening 32' in the head wall 26 corresponding to opening 32.

The outlet connection 37 for the main body portion of the air pump has an outwardly projecting portion 38 with a side opening 39 communicating with the air space in the header as in the case of the inlet pipe connection, as indicated in Figure 3. The outlet is of course in direct connection with the corresponding air space in the main body portion. The air spaces in the two sections are divided by integral partitions 40 in the head portion and 41 in the main body portion. The position of these partitions in the spaces viewed longitudinally of the axis of the rotor is indicated in dotted lines in Figure 5 there being inlet openings in the ends 23 and 26 of the rotor casing and corresponding openings 42 and 43 on that side of the partition 41 which receives the air from the inlet connection and thus there are inlet openings for the rotor from the air spaces in both ends of the casing. There are also corresponding openings 44 and 45 spaced around the circumference a material distance from the other openings which are on that side of the partition 41 which is in open communication with the outlet connection 37 and therefore the air leaves the rotor through these openings on both sides.

The water pump housing 12 includes the main body portion 46 which includes the volute casing 47 and the impeller 48 and the wall of the impeller on the side next to the air pump and a circular projecting portion 49 having an end contact surface 50 circular in form and surrounding an enlarged central

opening in the end wall of the water pump housing. The contact surface 50 fits the corresponding contact surface 51 on the adjacent end of the air pump housing and these two sections of the housing are detachably connected together by cap screws 96, Fig. 1. This main body portion of the water pump has formed on it and as a part of it the inlet connection 52 for water, as will be seen in Figure 4, and the outlet or discharge pipe connection 53 is also a part of this body portion of the housing. The head portion 54 of the water pump includes as a part of it the outer wall 55 of the impeller casing and also the end wall 56 constituting the end closure for the housing, the walls 55 and 56 being spaced apart a material distance. It will be seen by reference to Figure 4 that the inlet connection 52 of the main portion has a flat side wall 57 through which there is an opening 58 at the outer side of the volute casing and that the head portion has an outwardly extending portion 59 fitting the outer face of the part 57 and having an opening therein corresponding to the opening 58 whereby the entering water may pass into the head portion on the outer side of the volute casing as well as on the inner side. The impeller 48 has a hub portion 62 mounted on the shaft 28 so as to rotate therewith its inner end abutting a shoulder 63 formed by the reduction in diameter of the shaft at that point and its outer end being held by a screw threaded nut 64 on shaft 28. Water enters the impeller on both sides of the casing at the hub. The end wall 56 of the head portion 54 has on its inner side an integral wall 65 which extends around the shaft 28 forming a chamber around the bearing connection in the end 56 and extending upwardly in the form of a channel or passageway 66 to the upper portion of the chamber in the head portion. The purpose of this is to guide any air which may leak into the housing through packing 67 in the end 56 to the upper part of the air pump so that it will not be drawn in by the impeller. In order that any air which may accidentally enter the housing of the water pump and that which may be drawn into the housing with the entering water when the level in the tank is too low may escape from the housing, the main body portion is provided with a passageway 68 extending over the upper top portion of the volute casing, as shown in Figure 3, and is connected by opening 69 to the upper part of the chamber in head portion 54 and there is a vent opening 70 in its upper portion adapted to be connected to pipe 15 and convey the air to the tank 10.

The chamber in the body portion of the air pump housing between the end wall 22 and the end wall 23 of the rotor casing is on the inlet side of the pump and thus the air in it during operation is always rarified due to the action of the rotor in drawing it out creating a partial vacuum. The opening 71 in the end wall 22 of the air pump is cylindrical in form and an integral sleeve is formed on the inner face of the wall extending it inwardly of the air pump housing 70 a material distance. It is not necessary to use packing or to have a tight joint between the shaft 28 and this opening 71 since as above stated, the air in the air pump at this point is under partial vacuum and will not pass into the water pump. Such water as passes through the opening will serve to furnish the supply for the air pump. The end of the drive shaft projecting beyond the end of the air pump is supported by a ball bearing 72 carried by a bracket 73 which has a ring-like portion 74 fitting bearing surfaces on the end of the header portion 25 of the air pump housing and having longitudinally inclined arms carrying at their outer ends a sleeve 75 which has the ball bearing within it. Collars 76 and 77 are secured to the sleeve 75 fitting its ends and having central openings through which the shaft passes the ball bearing being between them. The inner raceway 78 of the ball bearing is held in stationary position by a shoulder on the shaft formed by a slight reduction in diameter at that point and by the screw threaded nut 79 on the outer side. The outer raceway 80 is movable longitudinally with the shaft to a limited extent, its movement being limited by collars 76 and 77. The end of the shaft 28 projecting from the water pump has an anti-friction bearing 81 mounted in a bracket similar to that just described with a ring-like portion 82 detachably connected to the end wall of the header portion of the water pump by bolts 83 through radially extending lugs or projections, as shown in Figure 2. The bracket 73 is secured to the air pump head portion by similar means. The raceways of bearing 81 are in stationary position, the inner raceway being held between a shoulder on the end of the shaft formed by a reduction in diameter of the outer portion and a screw threaded nut 84. The outer raceway is held in position by two ring nuts 85 having spaced holes 86 in their outer sides for locking and turning. A cap 87 fits the inner face of the sleeve 88 which is carried by the bracket and has a central opening surrounding the shaft and a projecting pin 93 entering one of the holes 86 in the ring nut to hold it in adjusted position and the cap 89 constitutes a closure for the outer end of the sleeve across the end of the shaft, and is provided with a pin 94 entering a hole in the adjacent ring nut to hold it in fixed position. The caps 87 and 89 when placed in position with their pins 93 and 94 in holes in the ring nuts 85 may be used to turn and adjust those nuts. It will be noted that the roller bearing 81 is the only bearing in either casing adapted to prevent longitudi-

dinal movement of the shaft therein and thus a slight longitudinal movement of the shaft in the other bearings is permitted. As will be seen by reference to Figures 1, 3 and 4 the housing 17 and head portion 25 of the air pump are detachably connected together by means of integral peripheral flanges 97 and 98 at their meeting ends provided with aligned radial slots 99 in which bolts 100 fit.

10 It will be noted that the shaft 28 varies in diameter having the largest diameter where it passes through the end wall 22 of the air pump and the arrangement is such that the different parts of the two pumps through 15 which it passes may be brought to position over the ends of the shaft in proper succession. The brackets carrying the bearings may be removed from the shaft and from the head portion of the pump or may be 20 removed with the head portions. It will be noted that the head portion 54 has a marginal flange 91 with a surface in a radial plane fitting a corresponding surface on the body portion 68 and may be detachably secured 25 to the body portion by bolts 92 passing through this flange or by other means.

In assembling impeller 48 of water pump can be properly adjusted axially by means of the adjustable bearing 81. The shaft 28 is 30 slideable in the rotor of the air pump although keyed to rotate therewith, and the bearing 75 permits axial movement of the shaft, so the bearing 81 is the only means for adjusting the rotor of the water pump. Furthermore the 35 improved construction of this bearing is such that a very delicate axial adjustment of the water pump rotor may be obtained. For this purpose the cap screws 105 are removed and the caps 87 and 89 turned carrying with 40 them the rings 85. If, as shown, there are four cap screws for each cap the rings can be turned any multiple of a quarter turn. If a finer adjustment is required then the pins 93 and 94 are inserted in different holes 86 45 after the rings have been adjusted.

The shaft 28 may be rotatively driven from any suitable source of power by any suitable means but a belt pulley 90 is shown for the purpose, it being attached to the outer end 50 of the shaft beyond the air pump.

Although one specific embodiment of the invention has been shown for purposes of illustration, it is to be understood that it is not limited to that particular form beyond 55 what is indicated in the following claims.

Having thus described the invention what is claimed as new and desired to be secured by Letters Patent is:

1. A combined unit for installation in a 60 gas and liquid system which requires gas and liquid to be simultaneously pumped, comprising in combination, a rotary gas pump, a rotary liquid pump, separate housings for each of said pumps, means for removably connecting said housings respectively to said system,

said housings being provided with mating surfaces whereby said housings may be removably and directly secured together end to end, permitting the housings to be separated and another gas or liquid pump substituted, and a common shaft for both of said pumps, whereby both of said pumps operate at the same speed. 70

2. In a gas and liquid system, the combination of a rotary gas pump and a rotary liquid pump provided with separate housings removably and directly secured together end to end whereby they may be separated, a part of the end wall of one forming a corresponding part of the end wall of the other, a single drive shaft extending through them, and means for connecting said pumps to said system. 75

3. A combined unit for installation in a gas and liquid system which requires gas and liquid to be simultaneously pumped, comprising in combination, a rotary gas pump, a rotary liquid pump, separate housings for each of said pumps, means for removably connecting said housings respectively to said system, said housings being provided with mating surfaces whereby said housings may be removably and directly secured together end to end, permitting the housings to be separated and another gas or liquid pump substituted, a common shaft for both of said pumps, whereby both of said pumps operate at the same speed, and detachable brackets secured to the outer ends of said housings carrying anti-friction bearings for said shaft, said detachable brackets facilitating the said substitution of the pumps. 85 90 95

4. A combined unit for installation in a gas and liquid system which requires gas and liquid to be simultaneously pumped, comprising in combination, a rotary gas pump, a rotary liquid pump, separate housings for each of said pumps, means for removably connecting said housings respectively to said system, said housings being provided with mating surfaces whereby said housings may be removably and directly secured together end to end, permitting the housings to be separated and another gas or liquid pump substituted, a common shaft for both of said pumps, whereby both of said pumps operate at the same speed, and removable outer head portions for each of said 100 105 110 115 120 125 130 housings permitting access to the interior of the main body portions.

5. A combined unit for installation in a gas and liquid system which requires gas and liquid to be simultaneously pumped, comprising in combination, a rotary gas pump, a rotary liquid pump, separate housings for each of said pumps, means for removably connecting said housings respectively to said system, said housings being provided with mating surfaces whereby said housings may 130

- be removably and directly secured together end to end, permitting the housings to be separated and another gas or liquid pump substituted, a common shaft for both of said pumps, whereby both of said pumps operate at the same speed, and means attached to the main body portion of one of said pumps for supporting the unit in elevated fixed position.
6. A combined unit for installation in a gas and liquid system which requires gas and liquid to be simultaneously pumped, comprising in combination, a rotary gas pump, a rotary liquid pump, separate housings for each of said pumps, means for removably connecting said housings respectively to said system, said housings being provided with mating surfaces whereby said housings may be removably and directly secured together end to end, permitting the housings to be separated and another gas or liquid pump substituted, a common shaft for both of said pumps, whereby both of said pumps operate at the same speed, removable outer head portions for each of said housings permitting access to the interior of the main body portions, brackets detachably secured to the outer ends of said portions and bearings in said brackets for the projecting portions of the shaft.
7. A combined unit for installation in a gas and liquid system which requires gas and liquid to be simultaneously pumped, comprising in combination, a rotary gas pump, a rotary liquid pump, separate housings for each of said pumps, means for removably connecting said housings respectively to said system, said housings being provided with mating surfaces whereby said housings may be removably and directly secured together end to end, permitting the housings to be separated and another gas or liquid pump substituted, a common shaft for both of said pumps, whereby both of said pumps operate at the same speed, brackets secured to said housings carrying bearings for said shaft, said shaft being so mounted in said gas pump housing and the bearing on the bracket attached to it so constructed as to permit slight relative longitudinal movement and the bearing on the bracket carried by the liquid pump housing being so connected to said shaft and the bracket as to prevent relative longitudinal movement.
8. A combined unit for installation in a gas and liquid system which requires gas and liquid to be simultaneously pumped, comprising in combination, a rotary gas pump, a rotary liquid pump, separate housings for each of said pumps, means for removably connecting said housings respectively to said system, said housings being provided with mating surfaces whereby said housings may be removably and directly secured together end to end, permitting the housings to be separated and another gas or liquid pump substituted, a common shaft for both of said pumps, whereby both of said pumps operate at the same speed, detachable brackets at the outer ends of said housings having ring-like portions concentrically surrounding said shaft having contact surfaces fitting corresponding contact surfaces of said ends, inclined spider arms connecting said ring-like portions to bearing sleeves for said shaft, and means for rigidly securing said brackets to said housings.
9. A combined unit for installation in a gas and liquid system which requires gas and liquid to be simultaneously pumped, comprising in combination, a rotary gas pump, a rotary liquid pump, separate housings for each of said pumps, means for connecting said housings respectively to the said system, the facing ends of said housings being provided with corresponding contact surfaces adapted to closely fit each other making a tight joint, means for rigidly securing said housings together with said surfaces in contact, and a single drive shaft extending through both housings.
10. A combined unit for installation in a gas and liquid system which requires gas and liquid to be simultaneously pumped, comprising in combination, a rotary gas pump, a rotary liquid pump, separate housings for each of said pumps, means for connecting said housings respectively to the said system, one end wall of said liquid pump housing having an enlarged central circular opening surrounded by a contact surface and said gas pump housing having at one end a contact surface closely fitting that of the liquid pump housing, means for rigidly connecting said housings together end to end with said surfaces in contact, and a single drive shaft extending through both housings.
11. A device of the character described, comprising in combination a rotary gas pump and a rotary liquid pump provided with separate housings, one end wall of said liquid pump housing having an enlarged central circular opening surrounded by a contact surface and said gas pump housing having at one end a contact surface closely fitting that of the liquid pump housing, means for rigidly connecting said housings together end to end with said surfaces in contact, and a single drive shaft extending through both housings, the said contact end of the gas pump housing constituting a part of its inlet chamber whereby no air can pass into the liquid pump housing around the shaft thus rendering packing between said shaft and end unnecessary.
12. A device of the character described, comprising in combination a rotary gas pump and a rotary liquid pump provided with separate housings secured with a watertight joint directly together end to end with the inlet chamber of the gas pump next to the liquid pump, a single drive shaft extending through said housings, bearings for

- said shaft carried by the outer ends of said housings on their outer sides, the openings in the outer end walls of said housings through which said shaft extends being provided with packing to prevent leakage and the corresponding opening in the intermediate wall between the housings being smooth and cylindrical without packing.
13. A device of the character described, comprising in combination a rotary gas pump and a rotary liquid pump provided with separate housings, one end wall of said liquid pump housing having an enlarged central circular opening surrounded by a contact surface and said gas pump housing having at one end a contact surface closely fitting that of the liquid pump housing, means for rigidly connecting said housings together end to end with said surfaces in contact, and a single drive shaft extending through both housings, the said contact end of the gas pump housing constituting a part of its inlet chamber whereby no gas can pass into the liquid pump housing around the shaft thus rendering packing between said shaft and end unnecessary, the outer end of the liquid pump housing having on its inner side an inwardly projecting wall forming a small chamber around the shaft and an upwardly extending passageway to guide any gas entering said housing around said shaft to the upper part of said housing and a vent opening at the top of said housing for the escape of said gas adapted to receive a discharge pipe.
14. A combined unit for installation in a gas and liquid system which requires gas and liquid to be simultaneously pumped, comprising in combination, a rotary gas pump, a rotary liquid pump, separate housings for each of said pumps, means for connecting said housings respectively to the said system, each of said housings including a main body portion having inlet and discharge pipes connected thereto and enclosing the rotary member and a detachable head portion having integral therewith the outer side wall of the casing of the enclosed rotary member, means for detachably and rigidly securing said body portions to each other end to end, and means for detachably securing said head portions to said body portions whereby access may be had to the rotary members without disconnecting or connecting pipes and whereby the pumps may be separated for substitution.
15. A combined unit for installation in a gas and liquid system which requires gas and liquid to be simultaneously pumped, comprising in combination, a rotary gas pump, a rotary liquid pump, separate housings for each of said pumps, means for connecting said housings respectively to the said system, each of said housings including a main body portion having inlet and discharge pipes connected thereto and enclosing the rotary mem-
- ber and a detachable head portion having integral therewith the outer side wall of the casing of the enclosed rotary member, means for detachably and rigidly securing said body portions to each other end to end and means for detachably securing said head portions to said body portions, brackets including ring-like portions fitting contact surfaces on the outer faces of said head portions around said shaft, sleeves carrying bearings for said shaft, spider arms connecting said ring-like portions and sleeves and means for detachably connecting said brackets to said head portions.
16. A combined unit for installation in a gas and liquid system which requires gas and liquid to be simultaneously pumped, comprising in combination, a rotary gas pump, a rotary liquid pump, separate housings for each of said pumps, means for connecting said housings respectively to the said system, a single drive shaft extending through them, each of said housings including a main body portion having inlet and discharge pipes connected thereto and enclosing the rotary member, and a detachable head portion having integral therewith the outer side wall of the casing of the enclosed rotary member, the end wall of said body portion of the pump housing having an enlarged central circular opening surrounded by a projecting contact surface fitting a contact surface on the end of the body portion of the other pump housing and detachable means for rigidly connecting said portions with said surfaces in contact and means for detachably securing said head portions to said body portions whereby access may be had to the rotary members without disconnecting or connecting pipes and whereby the pumps may be separated for substitution.
17. A rotary water pump comprising a housing including a main body portion having the inlet and discharge pipe connections and enclosing the rotary member, and a detachable head portion having integral therewith the adjacent side wall of the casing of the rotary member but spaced therefrom forming a chamber between them, a drive shaft extending through said housing, means for detachably securing said head portion to said body portion, said head portion having on its inner side an inwardly projecting wall forming a small chamber around the shaft and an upwardly extending passageway therefrom to guide any air entering around said shaft to the upper part of said housing and an air vent pipe connecting at the top of said housing, and a chamber on the other side of said rotary member also in communication with said vent pipe.
18. In combination, a liquid pump constituting one of a series graduated in capacity, a gas pump constituting one of a similar series of gas pumps, said liquid pump and

said gas pump each having an housing constructed so that either may be secured to another of the opposite series to thereby form a single unit consisting of a combined liquid and gas pump. 5

19. In combination, a liquid pump constituting one of a series graduated in capacity, a gas pump constituting one of a similar series of gas pumps, said liquid pump having 10 a housing provided with a contact surface common to its series, and said gas pump having a housing provided with a mating surface common to its series, whereby either may be secured to another of the opposite series 15 to thereby form a single unit consisting of a combined liquid and gas pump.

20. In combination, a liquid pump having a housing and an impeller therein constituting one of a series graduated in capacity, a 20 gas pump having a housing and a rotor therein constituting one of a similar series of rotors, and a common shaft for said impeller and rotor, said impeller being provided with

a driving connection common to its series, and said rotor having a driving connection 25 common to its series, whereby either may be secured on the common shaft with another of the opposite series to thereby form a single unit consisting of a combined liquid and gas pump. 30

21. In combination, a gas pump and a liquid pump having separate housings, said liquid pump housing having an opening surrounded by a contact surface and said gas pump housing having a mating contact surface and a common drive shaft extending through said opening, the contact part of the gas pump housing constituting part of its inlet chamber whereby no air can pass into the liquid pump housing around the shaft, 35 thus rendering packing between said shaft and end unnecessary.

In testimony whereof I hereunto affix my signature.

IRVING C. JENNINGS.
